UNITED STATES PATENT OFFICE.

ALVIN C. McCORD, OF CHICAGO, ILLINOIS, ASSIGNOR TO McCORD AND COMPANY, OF CHICAGO, ILLINOIS, A CORPORATION OF NEW JERSEY.

JOURNAL-BOX.

1,299,845.

Specification of Letters Patent.

Patented Apr. 8, 1919.

Application filed January 27, 1917. Serial No. 144,988.

To all whom it may concern:

Be it known that I, ALVIN C. McCORD, a citizen of the United States, residing at Chicago, in the county of Cook and State of Illinois, have invented certain new and useful Improvements in Journal-Boxes; and I do hereby declare the following to be a full, clear, and exact description of the invention, such as will enable others skilled in the art 10 to which it appertains to make and use the same.

My present invention relates to journal boxes of the type wherein the top thereof is cast fast to a pressed steel or independently 15 formed metal cellar, and which construction is disclosed and broadly claimed in the prior patent to Ivar A. Randel, No. 1,077,159, entitled "journal box" and issued of date, October 28, 1913.

20 In the construction of the journal boxes of the above type it has hitherto been the custom to form the pedestal channels in vertically extended portions of the cast top. In accordance with the most approved and 25 satisfactory methods of making these journal boxes, it has been found desirable to make the molds in cores and to reverse the cellar in the mold in the operation of casting the top fast onto the cellar. The successful carrying out of this operation necessitates elimination of as much as possible of 30 the cast steel or metal of the top. I have found that this can be done and that a better box may be obtained by forming the pedestal 35 channels either entirely, or nearly so, in the sides of the pressed steel or metal cellar.

In the accompanying drawings which illustrate the invention, like characters indicate like parts throughout the several views.

40 Referring to the drawings;

Figure 1 is a side elevation of the improved journal box;

Fig. 2 is a front elevation thereof with some parts broken away and some parts sectioned;

Fig. 3 is a vertical section on the line 3—3 of Fig. 2; and

Fig. 4 is a plan view of the box with some parts sectioned on the line 4—4 of Fig. 1.

50 The pressed steel cellar is indicated, as an entirety by the numeral 5 and the cast top is indicated, as an entirety, by the numeral 6, but both the top and the cellar are of the "Master Car Builders" type, and for the

purpose of this case it is only necessary to 55 particularly note that the top is formed with depending side flanges 7 that embrace and are cast fast to the top or upper edge of the cellar and is further formed inside of the box with depending wedge stops 8 and side 60 stops 9. The sides of the cellar 1 are formed with vertical and parallel outwardly pressed corrugations 10 that form ribs on the outer face of the sides and afford the required pedestal channels 11. The pedestal channels 65 11 thus form and the ribs 10 extend to the extreme upper edges of the sides of the cellar. The cast top 6, in alignment with the upper extremities of the ribs 10, is formed with short outstanding ribs 10^a and between 70 them with a short channel 11^a that constitutes short upper end extensions of the complete pedestal channels. However, without the said features 10^a and 11^a, completely operative pedestal channels will be formed directly 75 on the sides of the pressed steel cellar.

By this arrangement, it is possible, without providing long extensions from the fast top, to provide long, vertically extended pedestal channels, it being simply a matter of 80 design as to how far down on the sides of the box the said channels are carried. Of course, the channels form ribs that may without additional cost, be formed in the sides of the box in the operations of otherwise pressing the sheet metal into the form 85 of the cellar.

The channels in the side of the box are herein designated as pedestal channels, but this expression is used in a broad and liberal sense to cover such construction when combined with pedestals on which the box would slide vertically, or when rigidly secured to fixed pedestals, columns, frame brackets, or the like.

90 What I claim is:

1. A journal box comprising a cellar and an independently formed top made fast thereon, said cellar having laterally open pedestal channels formed directly in the 100 sides thereof, and said top having laterally open supplemental channels aligned with the upper extremities of the channels formed in the sides of said cellar.

2. A journal box comprising a pressed metal cellar and a top cast fast thereto, said cellar having laterally open pedestal channels formed directly in its sides, the said top 105

having laterally open supplemental channels alined with the upper extremities of the channels formed in the sides of said cellar.

3. A journal box comprising a pressed metal cellar and a top cast fast thereto, said cellar having laterally open pedestal channels formed directly in its sides, and extended to the extreme upper edges of the sides of said cellar, the said top having laterally open

supplemental channels alined with the upper extremities of the channels formed in the sides of said cellar. 10

In testimony whereof, I affix my signature in presence of two witnesses.

ALVIN C. McCORD.

Witnesses:

A. H. WIEDEMAN,
C. J. COPELAND.
